UNITED STATES PATENT OFFICE.

JOHANN STUMPF, OF CHARLOTTENBURG, GERMANY, ASSIGNOR TO GENERAL ELECTRIC COMPANY, A CORPORATION OF NEW YORK.

STEAM-TURBINE.

No. 821,599.

Specification of Letters Patent.

Patented May 22, 1906.

Application filed February 24, 1903. Serial No. 144,680.

To all whom it may concern:

Be it known that I, JOHANN STUMPF, a subject of the King of Prussia, German Emperor, and a resident of 28 Rankestrasse, Charlottenburg, near Berlin, Kingdom of Prussia, German Empire, have invented certain new and useful Improvements in Steam or Gas Turbines, of which the following is an exact specification.

My invention relates to improvements in steam or gas turbines, and more especially to such turbines in which the pressure of the steam or compressed gas is transferred into streaming velocity, which is utilized in one or several bucket-rims. In such turbines the number of revolutions depends upon the number of bucket-rims to which the steam flows.

It often occurs that the number of revolutions of a turbine has to be altered or changed, especially in case the turbine is used for driving screw-propellers, pumps, or the like. In the turbines hitherto constructed the consumption of steam was always increased if the number of revolutions had to be reduced. In order to do away with this disadvantage, I provide my new invention, which consists in a turbine provided with several turbine-wheels or several rows of buckets in one turbine-wheel, means being provided for running the turbine with one or several rows of buckets, in which latter case shovels or buckets, so-called "return" buckets, are provided, which lead the steam leaving the buckets of one turbine-wheel into the buckets of the following one or in case of using one turbine-wheel with several rows of buckets into the buckets of the following row. For this purpose I construct a turbine with fractional supply—that is to say, a turbine in which the nozzle-rim is divided in several parts, each of which parts can be used for driving the turbine. In the first part of the nozzle-rim no return-buckets may be provided at all; in the second part one row of return-buckets may be provided, so that in case this part works two rows of turbine-wheel buckets are at work; in the third part two rows of return-buckets may be provided, so that in this case three rows of turbine-wheel buckets may be at work, and so on.

In order to make my invention more clear,

I refer to the accompanying drawings, in which—

Figure 1 is a vertical section of a turbine constructed according to my invention. Fig. 2 is a section of the same at right angle to the section shown in Fig. 1. Figs. 3, 4, and 5 are respectively cross-sections at lines $x x$, $y y$, and $z z$ of Fig. 2.

It will be seen from the drawings that in the example shown the nozzle-rim f' , provided with the nozzles f , is divided into three parts marked I, II, and III. For each part e' e^2 e^3 is provided, each receiving motive fluid from a conduit h . In the part I no return-buckets are provided, as will be seen from Fig. 3, taken on line $x x$ of Fig. 2. In the part II 70 one row of return-buckets is provided, as will be seen from the section $y y$, Fig. 4. In the part III two rows of such return-buckets are provided, as will be seen from the section $z z$, Fig. 5. b' b' b^2 are three turbine-wheels. 75

The effect of the turbine is as follows: If steam is admitted to the chamber e' , the steam will flow through the nozzles f , connected to this chamber e' , into the buckets of the turbine-wheel b . As in that part of the 80 nozzle-rim which is supplied with steam by the admission-chamber e' no return-buckets are provided, the steam leaving the buckets of the turbine-wheel b will not be further utilized. The turbine will therefore run with 85 a high number of revolutions, as the whole streaming velocity is utilized in one row of buckets. If the number of revolutions is to be reduced, the admission-steam is cut off from the chamber e' and is admitted to the 90 chamber e^2 , so that the steam impinges upon the turbine-wheel b through the nozzles f , connected to this chamber e^2 . As will be seen from the section Fig. 4, one row of return-buckets g is provided in this part of the 95 nozzle-rim, so that the steam leaving the buckets of the turbine-wheel b at that side at which the return-buckets g are situated is led into the buckets of the turbine-wheel b' . If the number of revolutions is still further to 100 be reduced, the steam is admitted to the chamber e^3 , so that the steam leaving the turbine-wheel b is by the return-buckets g and g' led into the turbine-wheels b' and b^2 .

If the number of revolutions of the turbine 105 is altered to the considerable extent attained

by the construction above described, losses arise in the turbine by the angle of delivery of the steam—that is to say, by the angle at which the inlet-nozzles meet the circumference of the turbine-wheel not being adjusted to the number of revolutions. These losses occur from shocks arising in the turbine, for in all turbines a certain dependence exists between the streaming velocity of the steam, the velocity of the turbine-wheel at the circumference of the same, and the angle of inclination of the inlet-nozzles. It is therefore clear that if the velocity of the circumference of the turbine-wheel be changed the angle of inclination of the nozzles should be adjusted to the velocity of the circumference of the turbine-wheel. I easily attain this according to my invention by adjusting the angle of inclination of the nozzles of each group to the number of revolutions with which the turbine revolves if the respective group of nozzles is at work. It will be seen from Fig. 2 that in the part I in which the turbine runs with the highest revolutions the angle of inclination of the nozzles f is the smallest, and in the part III in which the turbine runs with the lowest number of revolutions the angle of inclinations of the nozzles f is the largest.

It will be clear that the construction may be modified in different ways and that the invention may just as well be employed in turbines in which the steam leaving the buckets of the turbine-wheel is led back into the same turbine-wheel buckets.

Having thus fully described the nature of this invention, what I desire to secure by Letters Patent of the United States is—

1. In a steam or gas turbine, the combination with several rows of turbine-wheel buckets, a nozzle-rim consisting of one row of nozzles situated around the turbine-wheel, the nozzles of this nozzle-rim being divided in several groups, a separate steam-admission chamber for each group of nozzles and a different number of rows of return-buckets fixed to each group of nozzles, substantially as described and for the purpose set forth.

2. In an elastic-fluid turbine, the combination of wheel-buckets, devices for discharging motive fluid against the buckets, and other buckets which cause the fluid from one device to act on the wheel-buckets a greater number of times than the fluid from another device.

3. In a variable-speed turbine, the combination of rows of wheel-buckets, a nozzle discharging motive fluid against the initial row of buckets to produce a given speed, a second nozzle discharging motive fluid against the initial buckets to give a lower speed, and return-buckets coöperating with the second nozzle to cause the motive fluid to act on a greater number of buckets than the fluid from the first nozzle.

4. In an elastic-fluid turbine, the combina-

tion of wheel-buckets arranged in rows, nozzles for discharging motive fluid against the buckets in a manner to produce variations in speed, the passages in the nozzles being arranged at different inclinations with respect to the buckets, and other buckets arranged in sets and progressively increasing in number for conveying fluid from one row of wheel-buckets to the next and causing it to give up its energy in an increasing number of operations.

5. In an elastic-fluid turbine, the combination of a number of rows of wheel-buckets, a casing therefor, a nozzle for discharging fluid against the buckets to produce a given rotative speed, one or more other nozzles, and one or more serially-arranged buckets, co-operating with the last-mentioned nozzle or nozzles for conveying motive fluid from one row of wheel-buckets to the next to produce a decrease in the rotative speed.

6. In an elastic-fluid turbine, the combination with a number of rows of rotating wheel-buckets, and a shaft, of a plurality of nozzles arranged to discharge fluid against the buckets to produce a given rotative speed, one or more other nozzles, and one or more serially-arranged buckets, co-operating with the last-mentioned nozzle or nozzles for conveying motive fluid from one row of wheel-buckets to the next to produce a decrease in the rotative speed.

7. In an elastic-fluid turbine, the combination with a number of rotating wheels, of a plurality of nozzles arranged to discharge fluid against the wheels, the angle of discharge of the nozzles with respect to the buckets progressively changing to cause different rotative speeds of the wheel-shaft, and buckets for conveying fluid from one wheel-bucket to another.

8. In an elastic-fluid turbine, the combination of nozzles arranged in groups, wheel-buckets acted upon by the nozzles of said groups, and return-buckets which when in action coöperate with the nozzles and successively increase in number in serial relation from one group to the next to decrease the rotative speed of the wheel-buckets when in action.

9. In an elastic-fluid turbine, the combination of wheel-buckets, a plurality of closely-associated nozzle-passages arranged in groups, and presenting their discharge ends to the same row of wheel-buckets, the angle of the discharge-passages in each group being the same, but that of the groups varying one with respect to the other, and return-buckets coöperating with one or more of the groups to decrease the rotative speed of the wheel-buckets by causing the fluid to act an increasing number of times on the buckets.

10. In an elastic-fluid turbine, the combination of wheel-buckets, nozzles arranged in

groups to produce different rotative speeds, the angle of discharge of the nozzles in each group successively increasing with respect to the wheel-buckets as the rotative speed of the buckets is decreased, and means coöperating with certain of the nozzles to decrease the rotative speed of the buckets by causing the fluid to act a greater number of times before exhausting.

10 11. In an elastic-fluid turbine, the combination of peripheral wheel-buckets, a nozzle-rim which surrounds the buckets, nozzles arranged in groups in the rim which discharge

motive fluid tangentially against the buckets, and return-buckets supported by the nozzle-rim which successively increase in number as the rotative speed of the wheel-buckets is decreased.

In testimony whereof I have signed my name to this specification in the presence of two subscribing witnesses.

JOHANN STUMPF.
